UNITED STATES PATENT OFFICE.

HARRIET A. PARKER, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,918, dated May 2, 1882.

Application filed March 27, 1882. Term of patent 3½ years.

To all whom it may concern:

Be it known that I, HARRIET A. PARKER, of Boston, in the county of Suffolk and State of Massachusetts, have invented a new and original Design for Carpets, of which the following is a specification.

The nature of my design is fully shown in the accompanying photographic illustration.

The design is composed of free-hand floral and foliage ornamentation arranged loosely over a ground ornamented by conventional figures of various forms, as shown.

I claim—

The design for a carpet, substantially as shown and described.

In testimony whereof I have signed my name to this specification, in the presence of two subscribing witnesses, this 24th day of March, 1882.

HARRIET A. PARKER.
